UNITED STATES PATENT OFFICE.

RUDOLPH LORANG, JOSEPH ANDERSON, AND PEHR LARSSON, OF CHICAGO,
ILLINOIS.

GUITAR.

SPECIFICATION forming part of Letters Patent No. 440,882, dated November 18, 1890.

Application filed February 3, 1890. Serial No. 339,030. (No model.)

To all whom it may concern:

Be it known that we, RUDOLPH LORANG, JOSEPH ANDERSON, and PEHR LARSSON, all citizens of the United States, residing at Chicago, in the county of Cook, State of Illinois, have invented certain new and useful Improvements in Guitars, of which the following is a full, clear, and exact description.

The invention consists in certain features of novelty that are particularly pointed out in the claims hereinafter mentioned, being first fully described with reference to the accompanying drawings, which form a part of this specification, and of which—

15 Figures 1 and 2, taken together, show one of the improved guitars in vertical section on a more or less irregular longitudinal line passing through or near the center of the instrument. The head and greater portion of the 20 neck of the instrument are now shown. Figs. 3 and 4 are elevations of parts hereinafter more particularly referred to. Fig. 5 is a vertical transverse section on the line 5 5, Fig. 2, looking in the direction of the arrow. Fig. 25 6 is a perspective view of the tail-piece viewed from the under side.

The principal object of the present invention is to provide a guitar having a neck which can be readily removed from the body of the 30 instrument.

To this end the body B and neck N are formed separate, the finger-board F being of course rigidly secured to the neck. The inner end f of the finger-board projects considerably beyond the heel end h of the neck, so as to extend over and rest upon the sounding-board S, as is customary. Secured to this projecting portion f of the finger-board near its extremity is a metallic plate 1, from which 35 projects downward a notched plate or hook 2. The sounding-board and also a heavy block 3, which is securely glued to the under side thereof, are each provided with a slot 4 of sufficient dimensions to admit the hook 2. 40 Screwed or otherwise suitably secured to the block 3 are a pair of hangers 5, which are preferably formed of a single plate of metal bent to form three sides of a rectangle, (thus [ ]) its base portion being provided with a 45 slot 6, registering with slot 4. Journaled in

these hangers and confined against longitudinal movement is a shaft 7, one end of which is bent at right angles to form a crank 8, to the extremity of which is secured a bell-shaped head 9. The parts are so proportioned and 55 arranged that when in normal position this head is in the center of the sound-opening, and its top about flush with the sounding-board. It is plated and enhances rather than detracts from the appearance of the instrument. Upon the shaft 7, between the hangers 5, is secured a disk 10, having upon one of its faces a flange 11, which is eccentric with respect to the shaft, its extremity 11^x being farthest from the shaft. The object of this 60 eccentric is to engage the hook 2 for pressing and holding the end f of the finger-board firmly against the top of the sounding-board. This is accomplished by a quarter-revolution of the shaft. In the drawings the parts are 65 shown in the positions that they occupy when the finger-board is firmly locked in place. To release it, the shaft is given a quarter-turn in the direction of the arrow, (see Fig. 3,) which brings the crank-arm 8 to the position of the 70 dotted line x. This disengages the eccentric 75 11 from the hook 2, and the latter may be withdrawn. To lock the hook, operations the reverse of these are necessary. It will be understood that the object in making the flange 80 11 eccentric is to have it draw the hook 2 down so as to firmly press the finger-board against the sounding-board. Stops 12 are formed upon the periphery of the disk for limiting the movement of the shaft to a quarter- 85 turn.

To the extremity of the heel end of the neck is secured a metallic plate 13, from which, near the top, projects a hook 14, having its nose presented downward. Near the 90 bottom this plate is provided with a vertical slot 15, and at the rear of this slot a cavity or recess 16 is formed in the heel. 17 is a heavy block of wood securely glued to the inner surfaces of the end, the sounding-board, and the 95 back of the instrument. To this block is firmly secured by screws a metallic plate 18, which is let into the end of the instrument until its outer surface is flush therewith. The lower end of this plate is bent at right angles 100

to form a lip 19, which is let into the back in a similar manner. The top side of this plate is provided with a notch 20 for the reception of the shank of the hook 14, the block 17 being cut away opposite said notch for the admission of the toe of said hook.

Secured to or formed upon the rear side of the plate 18 are a pair of perforated brackets 21 and 22, in which a screw 23 is journaled, and by which said screw is confined against endwise movement. This latter may be accomplished by reducing the upper end of the screw to form a shoulder, which may bear against one side of the bracket 21, either directly or through the medium of a washer 24, and upon the other side of said bracket passing a pin 25 through the reduced portion of the screw. Any suitable or well-known means (of which there are many) may be employed to accomplish this result. Upon this screw is a nut 26, having a hook 27, whose shank 28 projects through a vertical slot 29 in the plate 18. Upon the lower extremity of the screw is a winding-post 30 for the reception of a key, whereby the screw may be turned. It will be seen that the nut is effectually prevented from turning, and that consequently any turning of the screw (which, as before seen, is prevented from moving endwise) will cause the nut to traverse it in one way or another.

In the drawings the parts are shown in the positions they occupy when the neck is secured in place. To remove the neck, the strings are first slackened and the hook 2 unlocked in the manner already described. A key (like an ordinary clock-key) is then applied to the post 30, and the screw 23 turns in the direction that will cause it to elevate the nut 26. The nut is elevated until the hook is disengaged from behind the plate 13, and is somewhat above the lower end of the slot 15. The heel end of the neck may then be slipped upward to disengage the hook 14 from behind the top of the plate 18, after which the neck may be deflected upward, so as to throw the heel outward from the body, and thus withdraw the hook 27 from the slot 15. This done, it only remains to remove the hook 2 from the slot 4, and the body and neck are separate. To secure the neck in place, operations the reverse of these are necessary. The slot 15 is so located and proportioned that in securing the neck in place the shank 28 of the hook 27 will come in contact with the plate 13 at the bottom of the slot 15, and thus the heel end of the neck may be drawn down with great force. The under sides of the toes of the hooks are inclined or wedge shape, the object being to cause them to draw toward them the plates with which they respectively engage. The block 17 is provided with a recess 31 for the accommodation of the mechanism behind the plate 18. In order to prevent dirt from entering this recess, the post 30 is surrounded by a short tube or barrel 32, whose upper end is soldered

to brackets 22, and whose lower end passes through a suitable perforation formed through the lip 19, to which it is also secured.

In an instrument having a removable head it is desirable that the strings be capable of ready detachment from or attachment to the body of the instrument. To this end, instead of passing each string through a separate eyelet in the sounding-board back of the bridge, they are all attached to a separate tail-piece 33, and the latter anchored to a tail-pin 34 through the medium of a tail-loop 35, in the manner which is usual in violins and banjos. The tail-piece consists of a piece of metal of approximately V shape, having its broader end bent downward and inward beneath the main portion of the plate and provided with a perforation for each string. The opposite end is bent back, so as to form an open eye or loop, and soldered to the under side of the main body of the plate. Two perforations are formed through each of the opposite sides of the eye for the passage of the two ends of the string of which the tail-loop 35 is formed, said ends being tied together under the tail-piece, as at 36. Preferably this tail-loop consists of a double strand of wire cord; but we desire to have it understood that this is not essential, as any suitable material for forming the connection may be employed.

To the end that the strings may be slackened readily, avoiding the necessity of slackening each one separately by its appropriate key at the head, the tail-pin 34 is made vertically adjustable. This is accomplished by mechanism in many respects similar to that already described for operating the nut 26.

17^x is a block similar to the block 17, and having a recess 31^x, similar in purpose to recess 31.

18^x is a plate differing from plate 18 only in that it extends up to the top of the instrument and has its upper end bent over on the top of the sounding-board, so as to form a rest for the tail-string 35. So, also, the parts 19^x, 21^x, 22^x, 23^x, 24^x, 25^x, 26^x, 28^x, 29^x, 30^x, and 32^x are similar to parts already described bearing similar reference-numbers; but instead of the hook 27 a screw threaded pin 37 projects from the shank 28^x, and onto this is screwed a grooved nut, constituting the head of the tail-pin. The slot 29^x is covered by a sliding plate 38, which has an opening just large enough to fit snugly the rectangular shank 28^x of the nut 26^x. The plate is thus caused to move with the nut and is of such size that it always covers the slot. The head of the tail-pin impresses against the plate and holds it to its place. It will be seen that by elevating or lowering the tail-pin all the strings will be simultaneously slackened or tightened, as the case may be, and this feature of the invention may be applied to instruments independently of any other feature of the invention.

When the instrument is once in tune, it

enables all the strings to be quickly slackened without disturbing their relative adjustments, so that when the instrument is again desired for use it can be put nearly in tune at a single operation—namely, by applying the key to the post 30^x and drawing the tail-pin down to its former position.

The various features of the present invention are of course applicable to instruments other than guitars.

Having thus described our invention, the following is what we claim as new and desire to secure by Letters Patent:

1. In a guitar, the combination, with the body, the neck separate therefrom, and the finger-board secured firmly against the top of the sounding-board, of means for detachably securing the heel end of the neck to the body of the instrument, substantially as set forth.

2. In a guitar, the combination, with the body and the neck separate therefrom, having a finger-board projecting beyond the heel thereof, of means for detachably securing the projecting end of the finger-board against the top of the sounding-board and means for detachably securing the heel of the neck to the body of the instrument, substantially as set forth.

3. In a guitar, the combination, with the body having a slot through the sounding-board, of the neck separate therefrom, having the finger-board projecting beyond the heel end thereof, a hook projecting downward from the finger-board and through the sounding-board, a lock on the under side of the sounding-board for engaging said hook, and means for detachably securing the heel of the neck to the body, substantially as set forth.

4. In a guitar, the combination, with the body having a slot through the sounding-board, the separate neck having the finger-board projecting beyond the heel end thereof, and means for detachably securing the heel of the neck to the body, of a hook projecting downward from the under side of the finger-board through the sounding-board and an eccentric beneath the sounding-board adapted to engage and disengage said hook, substantially as set forth.

5. In a guitar, the combination, with the body having a slot through the sounding-board, the separate neck having the finger-board projecting beyond the heel end thereof, and means for detachably securing the heel of the neck to the body, of a hook projecting downward from the finger-board and through the sounding-board, a lock beneath the sounding-board, and a prehensile device for operating said lock accessible through the sound-opening, substantially as set forth.

6. In a guitar, the combination, with the body having a slot through the sounding-board, the separate neck having the finger-board projecting beyond the heel end thereof, and means for detachably securing the heel of the neck to the body, of a hook projecting downward from the finger-board and through

the sounding-board, an eccentric foreengaging said hook, and a shaft carrying said eccentric and having a crank for turning it, substantially as set forth.

7. In a guitar, the combination, with the body having a slot through the sounding-board, the neck having the projecting finger-board, and means for detachably securing the heel of the neck to the body, of a hook projecting downward from the finger-board and through the sounding-board, a lock situated beneath the sounding-board for engaging said hook, and a shaft for operating said lock, having the head 9, situated in the sound-opening, substantially as set forth.

8. In a guitar, the combination, with the body having a slot through the sounding-board, the separate neck having the projecting finger-board, and means for detachably securing the heel of the neck to the body, of the hook 2, projecting from the finger-board downward through the sounding-board, the disk 10, having flange 11 for engaging said hook, the shaft 7, to which said disk is secured, having crank 8 and head 9, and the hangers 5, in which said shaft is journaled, substantially as set forth.

9. In a guitar, the combination, with the body having a slot through the sounding-board and a separate neck having the projecting finger-board, of the hook 2, projecting downward from the finger-board and through the sounding-board, the disk 10, having flange 11 for engaging said hook and stops 12 for limiting its movement, and the operating-shaft 7, to which said disk is secured, substantially as set forth.

10. In a guitar, the combination, with the body and the neck, of means for detachably securing the heel end of the neck to the body, consisting of a hook carried by one member and engaging the other, substantially as set forth.

11. In a guitar, the combination, with the body and the neck separate therefrom, of plates secured to their meeting faces and a hook carried by one member and engaging the plate of the other, substantially as set forth.

12. In a guitar, the combination, with the body and the neck separate therefrom, of a hook carried by one member and adapted to engage the other and means for moving said hook, substantially as set forth.

13. In a guitar, the combination, with the body and the neck separate therefrom, of a hook carried by one and engaging the other and a screw for actuating said hook, substantially as set forth.

14. In a guitar, the combination, with the body and the neck separate therefrom, of a plate carried by one member, a screw suitably journaled to said plate and confined against moving endwise, a nut on said screw, and a hook projecting from said nut and adapted to engage the other member, substantially as set forth.

15. In a guitar, the combination, with the body and the neck separate therefrom, of the plate secured to one member, a screw journaled to said plate and confined against moving endwise, and having a post for the reception of a key, and a nut on said screw having a hook adapted to engage the other member, substantially as set forth. 45
16. In a guitar, the combination, with the body and the neck separate therefrom, of a hook carried by one member and adapted to engage the other, a screw for operating said hook having a winding-post, and a barrel inclosing said post, substantially as set forth. 50
17. In a guitar, the combination, with the body and the neck separate therefrom, of the plate 18, secured to the body and having the slot 27, screw 23, journaled behind said plate, nut 26 on said screw having the hook 27, and the plate 13, secured to the heel end of the neck, adapted to be engaged by hook 27, substantially as set forth. 55
18. In a guitar, the combination, with the body and the neck separate therefrom, of the plate 18 and the screw-actuated hook 27, carried by the body, the plate 13, secured to the neck and adapted to be engaged by the hook 27, and the hook 14, secured to the neck and adapted to engage the plate 18, substantially as set forth. 60
19. In a guitar, the combination, with the body and the neck separate therefrom, of the plate 18 having notch 20, and the hook 27, carried by the body, and the plate 13, having slot 15, and the hook 14, carried by the neck, the hook of one member being adapted to engage the plate of the other, substantially as set forth. 65
20. In a musical instrument, the combination, with the strings and a tail-piece to which they are attached, of an adjustable tail-pin and a flexible connection between said tail-piece and tail-pin, substantially as set forth. 70
21. In a musical instrument, the combination, with the strings, of the tail-pin 34, the nut 26^x, from which it projects, and the screw 23^x for actuating said nut, substantially as set forth. 75
22. In a musical instrument, the combination, with the strings, of the vertically-movable tail-pin, the plate 18^x, having the slot 27^x, through which said pin projects, and the plate 38, carried by the tail-pin and covering said slot, substantially as set forth. 80
23. In a musical instrument, the combination, with the strings, of the vertically-movable tail-pin, the plate 18^x, having a slot through which the shank of said pin projects, the plate 38, carried by said pin, the nut 26^x, from which said pin projects, the screw 23^x for operating said nut, journaled behind the said plate 18^x and having the winding-post 30^x, and the barrel 32^x, surrounding said post, substantially as set forth. 85
24. In a musical instrument, the combination, with the body, the neck separate therefrom, means for detachably securing them together, and the strings, of a tail-pin, to which all of said strings are connected, said tail-pin being adjustable, so as to tighten or slacken all of the strings simultaneously, substantially as and for the purpose set forth. 90
25. A tail-piece consisting of a piece of metal of an approximately V shape, having its broader end bent downward and provided with a perforation for each string and its apex bent downward and under, forming a loop or eye, and two perforations passing through each side of said loop, substantially as set forth. 95
